UNITED STATES PATENT OFFICE.

CHARLES L. WEIL, OF ST. CLAIR, MICHIGAN.

DISPENSING RECEPTACLE.

1,243,021.

Specification of Letters Patent. Patented Oct. 16, 1917.

Application filed August 17, 1914. Serial No. 857,173.

To all whom it may concern:

Be it known that I, CHARLES L. WEIL, a citizen of the United States, residing at St. Clair, in the county of St. Clair and State of Michigan, have invented certain new and useful Improvements in Dispensing Receptacles, of which the following is a specification.

This invention relates to dispensing receptacles and comprises a box of any suitable material, such as card-board, metal or the like, having a body portion and a top provided with an opening and a pivotally attached spout arranged to be elevated for dispensing purposes and lowered within the confines of the receptacle principally for shipping and storing purposes, said spout preferably being provided with a valve-like member which in the normal upright position of the box is closed but which either by its own weight or by the weight of the material in the box, when the box is inverted, is opened so that the contents of the receptacles may be dispensed; all as more fully hereinafter set forth and as claimed.

It is a desideratum in the art to which this invention relates to provide inexpensive condiment cartons which may be used for dispensing the contents, and which when so used may be maintained in substantially sealed condition in order that the savoriness of the condiment may not be dissipated through contact with the air and in order that the contents may be insulated from contaminating influences such as insects.

The carton of my invention is provided with an opening having the edges arranged for the reception and retention of the movable and removable spout. This opening is preferably but not necessarily in the top. The spout is preferably made from a blank which when folded in position forms a chute and which is provided with retaining means whereby it may be inserted in the opening 45 of the carton and cooperate with the edges around the opening whereby the chute may be raised to an elevated position advantageous for pouring the contents of the receptacle and may be lowered to a closing position advantageous for sealing the receptacle from the atmosphere and for placing it in condition in order that it may be shipped in quantities. In its folded chute-like condition, the spout parts are provided with 50 means for holding it in position, not only in the receptacle against removal therefrom

but in the receptacle in two positions; that is, the elevated and lowered positions. The spout is preferably made from one piece of material when of paper, card-board or the like, seamed, scored or creased along certain lines for folding in such manner that the different folded parts may coöperate with each other to result in the chute-like form. Preferably when made from a single blank 65 it is creased to be folded in five main parts, and a separate part for forming the valve portion is stamped in such manner as to be attached to one of the main parts of the spout so that in assembled position all the 70 parts are held together without the use of any additional fastening element.

In the accompanying drawings showing one form of a specific embodiment of my invention and in the several views in which 75 similar reference letters designate corresponding parts,

Figure 1 is a perspective view of the box with the spout in lowered position ready for shipment;

Fig. 2 is a segmental section through the top portion of the box with the spout in elevation and in elevated position;

Fig. 3 is a view similar to Fig. 2 with the spout in section;

Fig. 4 is a vertical section through a top portion of the box and spout with the spout in lowered position;

Fig. 5 is a plan view of the blank used for forming the main portion of the spout; 90

Fig. 6 is a plan view of the tongue or valve member;

Fig. 7 is a perspective view illustrating the way in which the spout is placed in position in the box;

Fig. 8 is a section along line 8—8 of Fig. 2; and

Fig. 9 is a view similar to Fig. 8, showing a slightly modified construction.

In the drawing, reference numeral 1 100 designates a box or carton of paper, card-board, tin or the like, having the top 2 in which is formed the hole 3 having toward the rear end a tongue 4 and at either side the slits 5. This tongue 4 serves as a rest 105 for the rear end of the spout and is in effect a part of a hinge member. The spout (Fig. 5) is composed of a back 6, having an extension 7 which operates as a stop to prevent the spout dropping into the box (as 110 hereinafter explained), sides 8 and 9, and front sections 10 and 11 in the form of flaps.

The blank is formed adjacent to the member 6 with the stamped out portion designated as 12 and with ridges 13 struck either outwardly from the sides as is shown in Fig. 8 or inwardly as is shown in Fig. 9. When the ridges are formed as shown in Fig. 9, they will engage beneath the tongue 4. These ridges form retaining members for holding the spout against accidental removal from the opening of the box. Outwardly projecting ridges 13^a are similarly formed at the front of the spout to hold the same raised when adjusted as seen in Fig. 2. Front flap 11 is preferably longer than front flap 10 and the latter in forming the spout is first folded inwardly. Flap 11 is folded or attached over it. The inner flap 10 may be provided with a tongue 14 as a convenient means for attachment of the valve member hereinafter described, and flap 11 provided with an extension 15 which when bent outwardly slightly extends under the forward edge 16 of the hole in the top of the box limiting upward movement of the spout and preventing accidental removal when the spout is lifted to elevated position. In forming the spout from the blank shown in Fig. 5 it is first folded along lines A—B and C—D until the sides 8 and 9 are at substantially right angles to the back 6. Then flap 10 is folded over on line E—F and flap 11 is folded over the top of flap 10 along line G—H. These two flaps may be secured together in any desired way. Extension 15 of flap 11 is then bent outwardly as is shown in Figs. 2, 3, 4 and 7. This completes the spout and when it is to be used without its valve member it is ready for attachment to the carton.

The use of the valve member is decidedly to be preferred. This member M may be scored along line J—K a distance from the upward end 20 approximately corresponding to the distance between the upper corner made by extension 7 of back 6 and side 9 and the upper corner made by flap 11 and side 9. The valve member may be provided with a slot 17 at one end which when the valve is assembled in the spout is passed over the tongue 14 of flap 10; and such tongue bent downwardly to hold the valve in place, thus forming a convenient hinge. The portion 18, preferably longer than the distance from C to G, is bent outwardly. Flap 10, when the spout is in folded position, is preferably longer than flap 11 and therefore presents an upper edge 19 above the upper edge of flap 11, which acts in the nature of a stop for the lower portion 20 of the extension 18 of the valve member. When said member is assembled in its working relation with the spout, the extension 18 constitutes a closure for the discharge passage of the spout while the main body portion 18^a of said member constitutes a lever

for swinging the closure between its closed and open positions.

The spout preferably with its valve member is inserted in the hole in the box in the manner shown in Fig. 7. The bent over portion 15 may be conveniently first inserted under the front edge 16 of the hole, and the rear of the spout then lowered until the ridges 13 are forced past the edges of the hole. These ridges offer sufficient resistance so that the spout may not be accidentally withdrawn. The stamped out or cut-away portion 12 of the spout leaves an edge 21 which rests on top of the tongue 4 of the box. The edge 21, together with the tongue 4, forms in effect a hinge, or pivotal attachment. The edge 21 bears upon the tongue 4 when the spout is elevated and lowered. In operation when the spout has been inserted in place, it is only necessary to press upon the back 6 whereupon the sides 8 and 9 will descend into the interior of the box until the extension 7 of the back 6 rests against the forward edge 16 of the discharge aperture limiting the downward movement. To elevate the spout the finger nail is inserted under the extension 7 and the spout is raised until the extension 15 of flap 11 engages the under side of the front edge 16 of the box. This extension 15 therefore together with the ridges 13 constitutes the attaching means of the spout. In dispensing position when the box is inverted the contents will naturally tend to pour out of the spout. Either the weight of the material of the valve member M or the weight of the contents of the box, or both, will cause the valve member to fall outwardly and downwardly as is shown in dotted line in Fig. 3. This valve member is free to move as indicated because of its attachment to tongue 14 of flap 10 through its slot 17. Its weight causes it to assume normal closed position with the box in upright position and when the contents are not being dispensed. The back 6 of the spout may be seamed at 22 to provide a catch-like member for the edge 23 formed at the line J—K of the valve.

What I claim is:—

1. In a box, a spout adapted to be elevated to dispensing position and lowered to shipping position, said spout comprising a single piece of material folded upon itself in a chute-like form and a valve in said spout arranged to open when the box is inverted, and to close when the box is in upright position.
2. In combination with a box, a removable chute-shaped spout adapted to be elevated to dispensing position and lowered to shipping position, a valve within said spout arranged to open when the box is inverted and close by its own weight when the box is in upright position.
3. In combination with a box, a spout

adapted to be elevated to dispensing position and lowered to shipping position, a valve within said spout arranged to open when the box is inverted and close when the 5 box is in upright position.

4. A chute-shaped spout having an opening at the outer end thereof, a valve member comprising a lever portion pivoted at its inner end within said spout and arranged 10 to swing across said opening, and a closure for said opening extending at an angle from the outer end of said lever portion.

5. A chute-shaped spout having an opening at its outer end, a valve member comprising a closure for said opening and a lever portion extending at an angle from said closure and pivoted within said spout and arranged to lie diagonally across the inside of said spout when the valve is closed.

20 6. A chute-shaped spout having an opening at its outer end, a valve member within said spout comprising a lever portion pivoted within said spout and extending diagonally across the inside of said spout to 25 the edge of the opening which is downmost when material is being poured from the spout, and arranged to swing across said opening, and a closure for said opening extending at an angle from the outer end of 30 said lever portion.

7. In a box, a valve member, a spout made of a single piece of material having a substantially rectangular shaped back, two sides, and a front composed of two sections 35 integral with the sides and folded one upon the other, one of said sections being longer than the other, the front and back being spaced to form an outlet, means on one section for securing the valve member 40 thereto, said valve member provided with a turned over portion proportioned to close said outlet, and said turned over portion being arranged to engage the portion of the one of said sections which is longer than the 45 other section, and means on the spout for attaching it to the box.

8. A blank for spouts for dispensing receptacles comprising a substantially rectangular section for forming the back, two 50 substantially identical sections for forming the sides and two sections integral with the sides for forming the front, the sides being arranged for folding at substantially right angles to the back and the front section being arranged for folding at substantially right angles to the sides whereby a chute-like spout is provided, means on one of the sections for attachment of a valve, and a 55 valve having means for coöperating with the 60 means on said section whereby the valve may be movably secured in said spout.

9. A blank for spouts for dispensing boxes comprising a back section of substantially rectangular shape, two integral side sections terminating a short distance below the upper 65 edge of the back section, two front sections integral with the sides, one of said sections extending on one side a short distance above the point of extension of the section on the other side, the other section forming the 70 front having an integral member extending below the bottom edge of the other front section when folded and forming a stop to limit upward movement of the spout when in one position, means on the side sections 75 adapted to coöperate with edges of the opening in the box to prevent easy removal of the spout, the side sections extending a short distance below the back section whereby there is provided a recess and whereby the 80 bottom edge of the back section may rest upon the box top in either elevated or lowered position.

10. A blank for spouts for dispensing boxes comprising a back section of substantially rectangular shape, two integral side sections terminating a short distance below the upper edge of the back section, two front sections integral with the sides, one of said sections extending on one side a short distance above the point of extension of the section on the other side, and having a tongue 85 for attachment to a valve member, the other section forming the front having an integral member extending below the bottom 90 edge of the other front section when folded and forming a stop to limit upward movement of the spout when in one position, means on the side sections adapted to co-operate with edges of the opening in the 95 box to prevent easy removal of the spout, the side sections extending a short distance below the back section whereby there is provided a recess and whereby the bottom edge of the back section may rest upon the box in 100 either elevated or lowered position, a valve arranged to be attached to the said tongue 105 of one of the front sections and having a turned-over portion substantially as long as the distance between the top of the last said front section and the top of the back of the spout whereby one edge of said turned-over section may rest on the upper edge of the said other section, and a means for limiting the downward movement of the spout. 110 115

In testimony whereof, I affix my signature in the presence of two subscribing witnesses.
